ATTORNEY.

UNITED STATES PATENT OFFICE

ALFRED D. LUEHRMANN, OF ST. LOUIS, MISSOURI, ASSIGNOR OF ONE-HALF TO
FRANCIS X. MEEHAN, OF ST. LOUIS, MISSOURI

DEVICE FOR REGULATING THE INTENSITY OF ACTION OF MASSAGING OR EXERCISING MACHINES

Application filed July 11, 1928. Serial No. 291,865.

This invention relates to certain new and useful improvements in exercising or massaging machines, and has for its object the provision of novel means for adjusting the 5 end portions of the belt between the body of the user and the machine toward or from each other to vary the degree of the agitating action of the belt upon the body of the user.

In an application filed of even date here- 10 with in the name of Luehrmann and Meehan, the idea of making such adjustment is broadly claimed. The present invention is directed to the preferred form of such adjusting means referred to and illustrated in such 15 companion application.

As stated in said companion application, while many of these massaging and exercising machines are provided with means for reducing or increasing the severity of the agi- 20 tating action, the adjustment of the machine is not always easy, especially for women, and cannot be effected while the machine is in use. Further, some makes of machines have 25 no means whatever for adjusting the degree of the agitating action.

The present invention aims to provide simple and readily operative means for regulating the degree of the agitating action of the belt upon the body, and to this end, comprises 30 an adjusting device having two relatively movable members engaging the respective end portions of the belt, preferably through corresponding apertures provided in the latter, whereby, by manipulating said device to 35 draw the said end portions of the belt between the body of the user and the machine toward each other, the severity of the action of the belt may be decreased. Conversely, after a 40 given adjustment, by manipulating the device to increase the distance between the end portions of the belt, the severity of the action of the belt may be increased.

The invention is illustrated in the accom- 45 panying drawing, in which—

Figure 1 is a side view of an exercising belt with my improved adjusting device mounted thereon;

Figure 2 is a plan view of the same;

Figure 3 is a cross-section on the line 3—3

of Fig. 2, the nature of the view showing the adjusting device in front elevation;

Figure 4 is an enlarged sectional view of the ratchet mechanism; and

Figure 5 is a side view slightly in perspective illustrating the general use of the invention. 55

Referring now to the drawing, the numerals 1, 2 (Fig. 5) indicate, respectively, the hooks on the two arms of an exercising or 60 massaging machine, on which hooks the ends of a belt 3 are adapted to be removably secured. To this end, each end of the belt is provided with a loop 4, usually of leather, which may be readily inserted over the hooks 65 1 and 2. The belt 3 is preferably of canvas. When so applied and with the hooks 1 and 2 reciprocating rapidly in alternation, the belt will be drawn with great rapidity back and forth on the body of the user, produc- 70 ing a more or less violent agitation of the body, depending upon the degree of severity of the vibrating action employed. This action may be easily and conveniently regulated 75 by my improved device and without interfering with the operation, as will be apparent from the following description.

The numerals 5, 6, and 7 indicate, respectively, corresponding sets of eyeleted openings formed in the end portions of the belt 3 at corresponding distances from the ends thereof. That is to say, the corresponding apertures 5 are located at a comparatively short distance from the respective ends of the belt, the apertures 6 at a greater distance, 80 and the apertures 7 at the greatest distance 85 from the ends of the belt.

My improved adjusting device is made of metal, preferably, and comprises two telescoping or relatively movable members which are adapted to be inserted in one or the other of the sets of apertures 5, 6, and 7 in the end portions of the belt and to be adjusted in various positions to draw such end portions 90 of the belt toward each other. To this end, one member 8 of the device is formed of a metal bar having the shape, substantially, of an elongated U providing a head 9 and two legs 10, 11. The other member 12 of the device is of substantially the same shape, hav- 95 100

ing a head 13 and two legs 14 and 15. The legs 14 and 15 of the member 12 are hollow and are adapted to slidably receive the legs 10 and 11 of the member 8. The upper leg 11 of the member 8 is provided on its upper side with a series of ratchet teeth 16. The leg 14 of the member 12 is somewhat shorter than the lower leg 15 and has on its inner end an upright tubular projection 17 in which is mounted a ratchet pin 18 (Fig. 4) normally pressed into engagement with the teeth 16 of the leg 11 by a coil spring 19. The upper end of the projection 17 is screwthreaded and a cap 20 screwed on its outer end maintains the ratchet pin in proper position. The said ratchet pin projects through the upper end of this cap and has a head 22 by grasping which with the fingers the ratchet pin may be lifted out of engagement with the ratchet teeth to enable the two members of the adjusting device to be pulled apart and, if necessary, separated. This latter, of course, is necessary when first applying the device to the belt 3, in order to enable the respective legs of the two members of said device to be passed through the corresponding apertures 5, 6, or 7 of the belt. The ratchet teeth and ratchet pin co-operate in a manner to permit the two members of the adjusting device to be easily pushed inward, to bring the two heads 9 and 13 toward each other, in order to decrease the distance between the end portions of the belt, but to prevent the separation of the two members of the device after the same have been once adjusted. In the movement of the two members of the device toward each other, the heads 9 and 13 engage the outer sides of the two end portions of the belt to likewise draw such portions of the belt toward each other.

In operation, it will be seen that the adjusting device can be pulled apart a sufficient distance so that the end portions of the belt will run straight from the body to the hooks 1 and 2, as shown in Fig. 5, and the maximum severity of action afforded by the machine will result. Then, by simply pressing the two heads 9 and 13 toward each other, the ratchet pin will pass over the ratchet teeth 16 and the two end portions of the belt will be drawn a greater or less distance toward each other, as shown by Fig. 2, and will be maintained in this position by the engagement of the ratchet pin with the ratchet teeth. This, as stated, decreases the severity of the action, and further adjustments can be made either to further decrease the severity of the action or to increase the same, as will be understood.

I claim:

1. An adjusting device adapted to be mounted on and supported by the exercising belt of a massaging machine, comprising two slidably connected members each of which has a belt-engaging means, and releasable means

carried by one of said members and engaging the other for holding the two members in fixed relation to each other at will.

2. An adjusting device for exercising belts comprising a member having a head and two parallel tubular legs projecting therefrom, a second member having a head and two parallel legs projecting therefrom and slidably mounted in the legs of the first member, a series of teeth on one of said inner legs, and a co-operating ratchet carried by the companion tubular leg.

3. An adjusting device for the belt of an exercising or massaging machine in which the two ends of the belt are attached to the machine, comprising two telescoping members each of which is provided with a head for engaging the outer side of an end portion of the belt, and automatic means, releasable at will, carried by one of said members and co-operating with the other and operating to permit the two heads to be moved toward each other and to prevent them from separating.

4. In a massaging machine of the vibrating belt type, in combination with the exercising belt, two relatively movable members supported thereon engaging, respectively, the sides of the belt at points removed from its ends and adjustable toward each other to draw the engaged portions of the belt toward each other, and means for holding the said members to any position to which adjusted.

5. In a massaging machine of the vibrating belt type, in combination with the exercising belt, two relatively movable members supported thereon engaging, respectively, the sides of the belt at points removed from its ends, and adjustable toward each other to draw the engaged portions of the belt toward each other, and adjustable means for holding the said members to any position to which adjusted.

6. An adjusting device adapted to be mounted on and supported by the exercising belt of a massaging machine comprising two co-operating members movable toward and from each other, each of which has means for engaging the outer side of one end portion of the belt when the ends of the latter are attached to the machine, and automatic means, releasable at will, for preventing a separating movement of the two members after a relative movement thereof.

In testimony whereof, I have hereunto set my hand.

ALFRED D. LUEHRMANN.
